UNITED STATES PATENT OFFICE.

JOHN EMERINGER, OF RANDOLPH, NEBRASKA.

GEARING.

1,106,792.

Specification of Letters Patent.

Patented Aug. 11, 1914.

Application filed October 21, 1912. Serial No. 727,080.

To all whom it may concern:

Be it known that I, JOHN EMERINGER, a citizen of the United States, residing at Randolph, in the county of Cedar and State of Nebraska, have invented a new and useful Gearing, of which the following is a specification.

This invention relates to new and useful improvements in washing machines and more particularly to means for operating the same.

The object of the invention is the provision of operating mechanism which may be secured to the cover of any of the well known forms of washing machines and which will be simple in construction and easy in operation.

With these and other objects in view my invention consists in the following details of construction and combination of parts as will be more fully understood from the following specification and drawings, in which:—

Figure 1 is a front elevation with a section broken away to show the interior. Fig. 2 is a top plan view. Fig. 3 is a front view of the operating mechanism. Fig. 4 is a rear view of the operating mechanism, and Fig. 5 is a detail of the carriage guide.

In the drawings, the numeral 1 indicates the tub mounted upon the supports 2 and 3 is the cover hinged at 4. The cover is secured in closed position by means of the fastener 5 and a plate 6 is secured to the cover for supporting it when open. A support for a clothes wringer is shown at 7.

A vertical shaft 8 extends through the cover and on the lower end thereof is secured the agitator 9 and on the upper end is secured a double pulley 10. Plates 11 are secured to the cover as clearly shown in Fig. 5 and form a guide for the reciprocating carriage 12. The carriage 12 is provided with the upwardly extending projection 13, the object of which will be later described. Secured to the cover are the brackets 14 and 15 and pivotally supported in these brackets is the lever 16 having a hand hold on each end as clearly shown. The bracket 14 also forms a bearing for the upper end of the vertical shaft 8. A rod 17 is connected to

the lever at 18 and to the carriage at 19. A hook bolt 20 passes through the projection 13 on the carriage 12 and is adjusted by means of the nut 21. One end of a chain 22 is connected to the hook end of the bolt 20 and the opposite end passes partly around the upper half of the double pulley 10 and is connected at 23, as clearly shown in Fig. 4. A chain 24 is connected to the opposite end of the carriage at 25 and passes partly around the lower half of the pulley 10, in a direction opposite to that of chain 22, and is connected at 26 as shown in Fig. 4.

Having described the construction of the invention in detail it is thought that the operation will be clearly understood. When the lever 16 is operated the carriage 12 is reciprocated through means of the rod 17, and the chains 22 and 24 being connected to opposite ends of the carriage, and extending around the pulley in opposite directions, will impart an oscillatory movement to the agitator 9.

What is claimed is:

1. An actuating mechanism comprising a support, a vertical shaft extending through the support, a pulley secured to the shaft, a bracket secured to the support and forming a bearing for the top of the shaft, a second bracket secured to the support, guide plates secured to the support, a reciprocating carriage operating between the brackets and having flanges on the bottom operating beneath the guide plates, a lever pivotally supported by and between the two brackets and connected to the carriage, and means connecting the carriage and pulley for operating the shaft.

2. An actuating mechanism comprising a support, a vertical shaft extending through the support, a double pulley secured to the shaft, a bracket secured to the support and forming a bearing for the top of the shaft, a second bracket secured to the support, guide plates secured to the support, a reciprocating carriage operating between the brackets and having flanges on the bottom operating beneath the guide plates, a lever pivotally supported by and between the two brackets, and connected to the carriage, and means connecting the carriage and pulley

2
for operating the shaft, said means comprising a flexible band connected to one end of the carriage and one section of the double pulley, and a second flexible band adjustably connected to the opposite end of the carriage and to the other section of the pulley.

In testimony that I claim the foregoing

as my own, I have hereto affixed my signature in the presence of two witnesses.

JOHN EMERINGER.

Witnesses:

JOHN DWYER,
M. RIEDESEL.
